PILE FABRIC WEAVE

Garfield J. Underwood and John Crawford,
Amsterdam, N. Y., assignors to Mohawk Car-
pet Mills, Inc., Amsterdam, N. Y., a corpora-
tion of New York

Application February 10, 1932
Serial No. 591,994

1 Claim. (Cl. 139—401)

This invention relates to pile fabrics and is concerned more particularly with a novel pile fabric and a method of weaving it, the new fabric being superior to prior fabrics of the same general class in that it may be woven more tightly and with a smoother back, its pile tufts are bound more securely in place and present a more even appearance, and a better face yarn coverage is obtained. Also, the new fabric is cheaper to produce, since less material is required and less strain is imposed on the loom during the weaving operation, so that the productivity of the loom is increased.

The principles of the invention may be utilized to especial advantage in the weaving of pile fabrics of the Wilton type and accordingly a novel Wilton fabric woven in accordance with the invention will be described in detail for purposes of explanation. It is to be understood, however, that the utility of the invention is not limited to that particular type of fabric and many advantages are afforded by weaving pile fabrics of other types in the manner presently to be described.

Pile fabrics of the Wilton type as now commonly wove include stuffer warps, pile warps, weft yarns crossing above, between, and below the stuffer and pile warps, and two sets of binder warps which are interlaced in the fabric to pass above and below the weft yards and hold the fabric together. The formation of the pile tufts is effected in such fabrics by producing loops of the pile warps raised above the binder warps, and then cut, and in some Wilton fabrics, the pile warp used for forming the tufts passes under a weft shot at the back of the fabric immediately before or after the tufts are formed, so that the pattern is visible on the back of the fabric.

Ordinarily the weft yarns are inserted in the fabric in cycles corresponding in number to the rows of pile tufts and with a number of shots per cycle, for example, three with one shot lying above the pile warps, the second between the pile and stuffer warps, and the third below the stuffer warps. In such a fabric, the two sets of binder warps are woven into the fabric in such fashion that one set passes over the upper weft shot of one cycle and below the bottom weft shot of the next, while the other set passes below the bottom weft shot of the first cycle and over the upper weft shot of the second cycle, this alternation continuing throughout the fabric. In such a fabric, any difference in the tension on the two sets of binder warps causes the top weft shots to be bound into the

fabric with varying degrees of tightness, and since these weft shots bind the pile warps into the fabric, any variation in their binding action results in a variation in the length of the pile loops in successive rows, which in turn produces tufts of non-uniform length and a fabric which is defective.

In the formation of the pile tufts, the pile warps are looped over a wire resting upon a set of binder warps which has been raised by its heddle and, if the tension on the two binder warps is different, or if driving parts of the loom are worn so that the heddle mechanisms do not raise their sets of warp to the same height, the wires used for the formation of successive rows of loops will be bound by the yarn at different heights and under different tensions and when the wires are withdrawn to cut the loops and form tufts, the successive rows of tufts will be at different heights which will cause marks on the face of the fabric.

Still another difficulty encountered in the weaving of these fabrics with two fine chains or binder warps is that the sets of fine chains cross each other within the fabric at such an angle as to leave substantial spaces defined between the upper set and the lower set. These spaces must be filled with stuffer warps and pile yarns, and the smaller the spaces, the more compact will be the fabric. However, if it is attempted to reduce the size of these spaces by pulling the fine chains in a direction lengthwise of the fabric to bring the top and bottom weft shots closer together, the spaces become elongated lengthwise of the fabric so that the weave is spread out and the binding action of the fine chains is at least not improved and may be diminished.

We have found that the difficulties and disadvantages involved in the use of two fine chain or binder warps in prior fabrics may be avoided and better results may be obtained if only a single set of fine chain or binder warps is employed, provided these warps are manipulated in a novel manner, so that the warps pass over the top weft shot and under the bottom weft shot of each cycle and thus lie substantially vertically in the fabric. With such a weave, all of the weft yarns which serve to retain the pile tufts in place are bound by the same warps so that there can be no difference in the length of the tufts by reason of variation in the tension of the warps or the variation in their position in the fabric due to wear in the heddle mechanism, as is the case when two sets of warps are

employed. Also, in the new fabric, all the pile loops are of uniform length and all may be sheared at the same height so that defects in the fabric arising from an uneven or non-uniform pile are avoided. The use of a single set of fine chains interlaced in the fabric in the manner described not only makes it possible to produce a more compact fabric, since increased tension on the chains results in an increased binding action, but also the fabric may be woven with a shorter depth of pile and a better coverage of the face yarn is obtained.

For a better understanding of the invention, reference may be had to the accompanying drawing in which there is illustrated an enlarged section and somewhat conventionally a Wilton fabric woven in accordance with the principles of the invention.

The Wilton fabric illustrated is of the type which is woven with three shots of weft per row of tufts and it includes three sets of stuffer warps and five frames of face yarn. This fabric has been selected as typical of others of the same kind, and it is to be understood that the invention may be employed in connection with fabrics which contain other numbers of sets of stuffer warps and frames of face yarn and are woven with other numbers of shots per cycle. Also, the fabric illustrated is one in which the pile loops on the face of the fabric are cut and in which the pattern is visible on the back but it is immaterial whether or not the loops are cut and the pattern is visible on the back.

In the drawing, the three stuffer warps are designated 10 and the pile warps 11. In the fabric illustrated there are five sets of pile warps which may be of different colors so that by raising the warps of the different sets out of the fabric to produce pile loops at selected intervals, a pattern may be produced. The fabric includes three weft shots 12 per row of pile tufts with the bottom weft shot lying below the stuffer warps; the middle shot above the stuffer warps and below the pile warps, and the top weft shot above the pile warps. A single set of fine chain or binder warps 13 is also incorporated in the fabric and these binder warps pass above the top weft shot of each cycle and below the bottom weft shot of that cycle. At intervals, depending upon the pattern, the pile warps are brought upwardly above the fabric to form loops which, in the illustration, have been cut to form pile tufts 14, and immediately following the formation of each loop, the pile warps which have been used to form the loops are brought down to pass around a bottom weft shot as indicated at 15 so that the pattern appears on the back of the fabric.

It will be apparent that the upper weft shots which bind the pile warps in place are in turn

bound into the fabric by the fine chains 13, and these chains pass almost directly across the fabric from one face to the other instead of crossing the fabric at a relatively flatter angle, as would be the case if two sets of binder warps were employed. Also, the same set of binder warps holds the top and bottom weft shots against the body of the fabric and when the tension on the binder warps is increased, these weft shots are bound more securely in place, compressing the fabric, and making a tight compact weave. Such an increase in tension does not tend to elongate the new fabric, while a fabric in which two binder warps are employed is thus spread out by an increased in binder warp tension.

In the new fabric, a good face yarn coverage is obtained and the fabric has a tight back. Also, since there is a single set of binder warps and the pile loop wires rest on top of this set for the formation of each row of tufts, the fabric does not have uneven tufts.

The loom for weaving the new fabric is considerably simplified as only a single heddle mechanism is required, and the loom is under less strain, because the tension required on the binder warp beam may be reduced. The reduction in tension also reduces the likelihood of breakage of the warp threads which requires stoppage of the loom and piecing up, and the loom thus operates more efficiently, these factors further contributing to lowering of the cost of production.

We claim:

A three-plane pile fabric of the Wilton type comprising pile warps and stuffer warps extending longitudinally through the fabric, weft shots extending across the fabric in cycles with one shot per cycle lying on top of the idle portions of the pile warps, another shot per cycle lying beneath the stuffer warps, and at least one shot per cycle lying between the idle portions of the pile warps and the stuffer warps, the shots below the stuffer warps equalling in number the shots lying on top of the idle portions of the pile warps, and a single set of binder warps, each binder warp passing over the top of all the weft shots lying on top of the idle portions of the pile warps and beneath all the weft shots lying below the stuffer warps, portions of the pile warps being raised out of the fabric at points selected in accordance with a pattern to produce a pile and said pile warps so raised passing directly through the fabric from each of the points of raising and beneath a weft shot below the stuffer warps and thence back into the fabric, to produce a pattern on the back corresponding in appearance and position to the pattern on the face.
